UNITED STATES PATENT OFFICE.

MILTON T. HASEK, OF CEDAR RAPIDS, IOWA.

BOTTLE CAP.

Application filed October 13, 1925. Serial No. 62,313.

This invention relates to improvements in receptacle closures and has particular reference to a cap to be used upon bottles and the like.

5 An important object of the invention is the provision of a cap for milk bottles and similar receptacles formed so as to be conveniently bent outwardly in segmental form so that only a portion of the bottle may be 10 opened.

Another object of the invention is to provide a cap of the above character which may be partially opened in desirable segments.

15 A still further object of the invention is the provision of a cap formed so as to be conveniently crushed inward for removal or partial opening of the container.

Still another object of the invention is the 20 provision of a cap adapted to enclose a milk bottle or similar receptacle and designed so as to be partially folded so as to open a comparatively small portion of the receptacle when desirable.

25 Other objects and advantages of the invention will become apparent as the description progresses.

In the accompanying drawing forming a part of this specification and in which like 30 numerals are employed to designate corresponding parts throughout the same:

Figure 1 is a top plan view of a cap constructed in accordance with my invention,

Figure 2 is a bottom plan view of the 35 same,

Figure 3 is an enlarged transverse sectional view taken on the line 3—3 of Figure 2,

Figure 4 is a side elevation of the device 40 partially in open position shown mounted in association with a container, and

Figure 5 is a perspective view of the cap in a partially open position.

In the drawing, wherein for the purpose 45 of illustration is shown the preferred embodiment of my invention, the numeral 10 generally designates the bottle cap structure which is preferably of circular formation and constructed of card board or similar 50 material commonly of one or more sheets of the same.

As is well known to those familiar with the art, bottle caps are commonly of rigid construction so that when it is necessary to 55 open a milk bottle or other receptacle enclosed by the same, the entire cap is neces-

sarily removed. Thus the contents of the bottle are exposed to dust and germs to quite a large extent. My invention relates particularly to a cap designed to permit partial 60 opening so that only enough of the cap is raised to permit delivery of the contents. With this in mind, the bottom of my improved cap 10 is provided with a series of transversely extending grooves 11 preferably impressed about half way through the cap so that a portion of the cap may be 65 readily turned upward.

With particular reference to Figure 2, it 70 will be seen that my cap is preferably provided with a pair of central intersecting grooves 11 and 12 and a pair of grooves extending parallel with one of the central transverse grooves in spaced relation so as to divide the cap into segments less than one-half thereof. Each of these segments designed by the numeral 13 is capable of being raised so as to only partially uncover the milk bottle or other container but sufficient to permit delivery of the milk 75 80 therein.

It is evident, from the foregoing, that the cap after being securely mounted in the milk bottle may be raised by elevation of one of the end segments equal to practically one-fourth of the area of the delivery opening or, if desirable uncovering three-quarters, differing of course upon the amount of delivery found necessary.

It is thus apparent that a bottle cap of 90 simple yet efficient design is provided, tending to retain milk and similar matter in receptacles in more sanitary condition.

It is to be understood that the form of 95 my invention herewith shown and described is to be taken as the preferred example of the same and is readily susceptible of modification so that changes as to the shape, and arrangement may be resorted to without departing from the spirit of the invention or 100 the scope of the subjoined claim.

Having thus described my invention, I 105 claim:

A milk bottle cap of circular formation having its under surface provided with a single centrally arranged groove extending from edge to edge, and a group of grooves extending across the central groove from edge to edge of the bottle cap and at right angles to the central groove.

110 In testimony whereof I affix my signature.

MILTON T. HASEK.
